IRONING MACHINE CONTROL

John A. Castricone, Peoria, Ill., assignor to Alter-
fer Bros. Company, Peoria, Ill., a corporation of
Illinois

Application September 8, 1939, Serial No. 293,987

5 Claims. (Cl. 38—47)

The present invention relates to ironing machines and more particularly to an improved control mechanism for any conventional roll type ironer.

When clothes have been damped preparatory to ironing, it will be realized that it is a practical impossibility to accomplish an entirely uniform dampening of all parts of a garment, but at the same time the operation or ironing must complete the drying of all portions of the garment. It is, therefore, highly desirable that the ironer control mechanism be of such design that the rotation of the roll may be momentarily interrupted to provide spot ironing in order that the application of heat from the ironing shoe may be prolonged while certain unduly dampened or unusually heavy portions of the garment are in engagement between the roll and shoe, in order that the heat of the shoe be utilized to complete the drying of the garment.

This type of ironing machine control has been provided in the prior art, but has been found to be somewhat objectionable for the reason that a stationary pressing does not provide an entirely satisfactory surface finish on the work, and it appears that the only way commonly known at the present time by which the desired surface, sheen and finish may be given the work is by pressing under a heated ironing shoe, which is maintained in constant surface movement relative to the work.

It is, therefore, a primary object of this invention to provide a roll-type ironing machine wherein the desired relative movement between the roll and shoe is normally accomplished by the advancing of work along the normal path of feed of the machine with feed interrupting means and with burnishing means, whereby relative movement between the roll and shoe may be maintained whenever the feeding movement of the roll is interrupted.

A further object of the invention is to provide an ironer control mechanism as outlined above, in which a foot pedal may be operated in such a manner as to momentarily interrupt the feeding movement of the roll while the roll and shoe are in engagement and to automatically cause the roll and shoe to begin to move relative to each other and to continue this relative movement while the feeding movement is thus interrupted.

A further object of the invention is to provide an ironer control mechanism wherein the ironing shoe and roll may be moved in a reciprocating movement in a path parallel to the axis

of the roll to maintain relative movement between the roll and shoe when the feeding movement of the roll is interrupted.

Another object of the invention is to provide an ironer driving means and control therefor of such design that the ironer roll may be released from its driving mechanism in such a manner as to be free from manual rotation to advance the work, and having mechanisms effective to accomplish relative movement between the ironing roll and shoe while the roll is thus released.

Other objects will appear hereinafter and will become readily apparent by an examination of the following specification and drawings in

15 which:

Fig. 1 is a front elevation of an ironing machine cabinet;

Fig. 2 is an end elevation of the ironing machine cabinet illustrated in Fig. 1;

Fig. 11 is a detail sectional view taken substantially on the plane of the line 11—11 of Fig. 10;

40 Fig. 12 is a detail sectional view of the ironer control clutch mechanism being taken substantially on the plane of the line 12—12 of Fig. 9; and

Fig. 13 is a detail sectional view similar to Fig. 45 12, showing the several parts of the structure in a changed position.

The roll drive mechanism

Referring now more particularly to the drawings, the entire ironer mechanism is mounted in the cabinet 10, which preferably comprises legs 11, a worktable 12 and a top or cover member 13. The arrangement is such that the top 13 may be removed to provide an unobstructed working surface on the table 12.

The ironer mechanism comprises an ironing bed, which is preferably in the form of a roll 15, rotatably mounted on a roll bracket 16 formed integral with a gear case 17 and secured in any suitable manner to a table portion 12 of the cabinet 10. The roll 15 is rotatably driven by means of a motor 18 which operates through certain power transmission mechanisms housed within the gear case 17 and the roll bracket 16. The motor shaft 19 is connected by means of a suitable coupling 21 to the lower end of a worm gear shaft 22 supported between the lower bearing 23 and an upper bearing 25. The lower bearing 23 is bolted to the gear case 17 by means of cap screws 24, and the upper bearing 25 is formed integral with the top wall of the gear case. A worm 26 is formed adjacent the upper end of the worm gear shaft and drives a worm gear 27 mounted on the sleeve 35 for free rotating movement on a shaft 28 secured between a boss 29 formed in the wall of the gear case 17 and a plate 31 secured between bosses 32 in the gear case 17 by the cap screws 33. The worm gear 27 constantly meshes with a lubricating gear 30, which serves to carry lubricant from the sump 26 in the gear case 17 to the gear 27.

A driving connection between the worm gear 27 and a pinion gear 34 is established by the sleeve 35, which is rotatably mounted on the shaft 28 and which carries the worm gear 27 and the pinion gear 34 secured in position by means of a key 36. The pinion 34 meshes with and drives idler gear 38 mounted on a stub shaft 39, secured in a boss 41 of the gear case 17 in order to transmit rotary movement from the pinion 34 to a driven gear 42, mounted on the ironer roll drive shaft 43. One end of the roll drive shaft 43 is rotatably mounted on a stationary bearing 44 carried by a bearing support plate 45 bolted to suitable bosses 46 on a gear case 17 by means of the cap screws 47. The opposite end of the roll drive shaft 43 is freely rotatable within the bushing 48 carried in a boss 52 formed in the wall of the gear case 17. The arrangement is such that the continuous rotary movement of the motor shaft 19 is transmitted by means of the worm gear 26 to the worm wheel 27, thence through the sleeve 35 to the pinion 34 and through the idler gear 38 to the driven gear 42 in order to impart continuous rotary movement to the roll drive shaft 43, and a clutch mechanism is provided whereby the motion of the roll drive shaft 43 may be transmitted to the roll 15 as will be hereinafter described.

This clutch mechanism 59 includes a driving element 61 keyed to the roll drive shaft 43 and secured thereon by means of the set screw 62, and a driven clutch element 63 mounted for free rotation and longitudinal sliding movement on the roll drive shaft 43 at a point between clutch driving member 61 and the stationary bearing 44. The driven clutch element 63 includes gear teeth 64 which are adapted to mesh with corresponding internal gear teeth 65 formed on a cap 66 rigidly secured to the driving clutch member 61. Thus, when the gear teeth 64 are in engagement with the internal gear teeth 65, the rotary movement of the roll drive shaft 43 is transmitted through the clutch 59 to the driven sprocket wheel 68, and thence to the ironer roll 15 through the medium of the chain 71, the sprocket 72, the sprocket 73, chain 74 and roll shaft sprocket 75.

Disengagement of the clutch 59 will be accomplished by moving the driven clutch element 63 longitudinally along the shaft until the gear teeth 75

64 disengage the internal gear teeth 65. This longitudinal movement of the clutch element 63 may be accomplished either automatically or manually at the will of the operator as will be hereinafter described.

The synchronous control mechanism

When the ironer roll 15 is being driven, the ironer shoe 101 should be held in firm pressure relationship with the roll in order to effect the proper pressing of the work passing between the roll and the shoe. For this reason it is desirable that a single manual control be provided of such design that the actuation of the control will cause the roll 15 to begin its rotary movement and will simultaneously bring the shoe 101 into proper pressure relationship with the roll. To accomplish this result, a notched disk or driving clutch element 102 is rigidly secured to a hub portion 103 of the worm gear 27 in such a manner as to rotate constantly at all times when the motor 18 is in operation. The driven clutch element comprises a casting 104 in which a transverse slide plate 105 is mounted. The slide plate 105 is secured in position by means of the set screws 106 and washers 107 and carries a latch plate 108 including a tooth 109 which is adapted to engage a toothed disk 102. It will be seen from Fig. 12 that the slide plate 105 is capable of sufficient transverse movement that the tooth 109 may engage or disengage the toothed disk 102 at different periods of operation of the machine. To permit this transverse movement, an elongated opening 111 is formed in the slide plate 105 in order to clear the shaft 28 and the hub 110 of the casting 104.

To actuate the slide plate 105, a rocker arm 112 is mounted for free rotation on the hub 110 of the casting 104 and is secured in the recess 113 between the body of the casting 104 and the slide plate 105. During the normal operation of the machine, one of the downwardly extending dogs 114 or 115 will be engaged and held in stationary position by the stop arm 116 which is pivotally mounted on the stub shaft 117 and resiliently held in engagement with the rocker arm 112 by means of the tension spring 118 anchored on a bracket 119 of the supporting plate 45. At this time it will be clear that none of the external parts of the machine will be in motion since the driving force transmitted to the motor 18 will be effective only to rotate the several gears and shafts in the gear case 17, but will not drive the roll 15 due to the fact that the clutch mechanism 59 is in its disengaged position.

When the operator desires to start the machine, she will actuate the knee control 121 which is effective to engage the tooth 109 with the toothed disk 102 in such a manner that the casting 104 will be driven through one-half of a revolution of movement. This movement will result in engaging the clutch 59 to establish the driving connection with the roll 15 and simultaneously cause the ironer shoe 101 to move into engagement with the roll 15. The knee control 121 is pivotally mounted on the pin 122 and when it is actuated by the operator, the motion will be transmitted through the link 123 on the control lever 121 at 124 to a control arm 125 secured to a stub shaft 126 journaled in the removable end plate 78 of the gear housing 17. If desired, a lug 127 may be formed on the end plate 78 and positioned between the bifurcated end portions 128 of the arm 125 in such a man-

ner as to limit the arcuate movement of the arm 125 and consequently limit the movement of the stub shaft 126. When the knee control lever 121 is thus actuated, the partial rotation of the stub shaft 126 will cause the control arm 125 to exert an upward force on the tie rod 132 in such a manner as to lift the free end of the stop arm 116 upwardly against the tension exerted by the spring 118 and allow the operating end of the arm 116 to release the dog 115. The tension spring 133 which extends between an anchor pin 145 on the rocker arm 112 and one of the screws 106 on the casting 104, will then exert sufficient tension to pivot the rocker arm 112 about the hub 110 of the casting 104 in a counter-clockwise direction, as viewed in Fig. 13. At that time a pin 145, which is stationarily secured to a rocker arm 112 and freely movable within a slot 136 in the slide plate 105, will cause the slide plate 105 to move to the left, as viewed in Fig. 13, in such a manner that the tooth portion 109 and the block 108 will engage the toothed disk 102. It will be understood that the toothed disk 102 is rotating at all times and that when the tooth 109 engages the disk 102, the entire casting 104, together with all its associated parts is caused to rotate in a counter-clockwise direction until the dog portion 114 of the rocker arm 112 is engaged by the stop arm 116. In this connection it should be pointed out that in operating the machine the operator will depress the knee control lever only momentarily in such a manner that when the stop arm 116 disengages the dog 115 it will immediately move back to its original position in time to be engaged by the dog 114 when the casting 104 and its associated parts have moved through approximately one half of a revolution of movement. As the dog 114 engages the stop arm 116, the casting 104 will momentarily continue its rotary movement with the result that the continued movement of the casting 104 will cause the tension spring 103 to be elongated and the rocker arm 112 will pivot about the hub 110 of the casting 104 so that the pin 135 will move the slide plate 105 back to the position shown in Fig. 12 and will thus disengage the tooth 109 from the toothed disk 102 and stop rotation of the casting 104 and its associated mechanism.

From the above it should be clear that each time the knee control lever 121 is actuated, the casting 104 and its associated mechanisms will rotate through one half of a revolution of motion and come to a stop until such time as the knee control lever 121 is again actuated. This movement of the casting 104 accomplishes two purposes; the first being to engage or disengage the clutch mechanism 59 controlling the rotary movement of roll 15, and the second being to simultaneously move the heated ironing shoe 101 into or out of engagement with the roll.

The roll drive clutch control

To actuate the clutch 59, a cam surface 141 is formed on the casting 104 and is adapted to engage the cam extension 142 on a shifting yoke 143 secured at the end of the slide shaft 144 by means of a cap screw 145. As will be seen in Fig. 8, the outer end of the slide shaft 144 is supported for longitudinal movement in a bearing 146 in the support plate 45, while the inner end of the shaft 144 is slidably mounted in a suitable bearing 147 formed in the wall of the gear case 17. A spring 148 tends to urge the shaft 144 outwardly in order that the shifting yoke 75

143 which engages an operating groove 149 in the movable clutch element 63 will normally hold the clutch element 63 in such a position that the gear teeth 64 are in engagement with the gear teeth 65 (see Fig. 9). However, when the casting 104 rotates and the cam surface 141 engages the cam extension 142, the slide shaft 144 will be moved inwardly and the shifting yoke 143 will disengage the elements of the clutch 59 to break the driving connection to the ironing roll 15.

The pressure engaging means

The means for moving the ironing shoe 101 in a pressure engagement with the roll 15 comprise an eccentric 151 which is formed as an integral part of the casting 104 and which carries an eccentric strap 152 provided with an elongated slot 153 through which a pin 154 carried by the crank 155 may be positioned, in order that the movement of the eccentric may exert pressure on the pin 154 through the medium of a coiled compensating spring 156 housed between the walls 157 and 158 of the eccentric strap 152. The crank 155 is carried by a rock shaft 161 journaled in suitable bearings 162 in the gear case 17 and extending longitudinally of the machine to a point adjacent a pair of stationary ironer shoe supports 163.

These ironer shoe supports 163 are secured to the frame of the ironing machine in any suitable manner and each carries at its upper end an ironing shoe arm 164, which is pivoted for universal movement with respect to the stationary support 163, as will be hereinafter described. The arms 164 support the ironing shoe 101 and in the normal operation of the machine this shoe will be automatically moved into engagement with the roll 15 whenever the roll begins to rotate and will be moved out of engagement with the roll whenever the roll ceases its rotary movement. This automatic movement of the ironing shoe 101 is accomplished by providing the rock shaft 161 with a pair of crank arms 171 carrying crank pins 172 on which the connecting rods or links 173 are mounted. The upper end of each of the connecting rods 173 is mounted on a cross pin 174 stationarily carried by each of the arms 164. The arrangement is such that whenever the eccentric 151 moves to the position shown in the drawings, the spring 156 will exert a resilient pressure against the pin 154 tending to rock the shaft 161. This rocking movement of the shaft 161 will be transmitted through the cranks 171, the connecting rods 173, and the pins 174, in such a manner as to pivot each of the arms 164 downwardly and cause the ironing shoe 101 to resiliently engage the roll 15. The parts will remain in this position until such time as the knee control lever 121 will again be actuated in order to stop the roll 15 and disengage the ironing shoe 101. When this is done it will be clear that the casting 104 will again move through one half revolution of movement which will result in relieving the pressure exerted between the shoe 101 and the roll 15 by the eccentric 151. This movement of the eccentric 151 will operate to withdraw the shoe 101 to a predetermined spaced relationship with the roll 15 and will also cause the cam 141 to disengage the clutch 59 and stop the rotary drive to the roll 15. A pair of tension springs 175, each of which extends between one of the pivot pins 165 and the anchor pin 176, carried on the connecting rods 173, will assist in moving the connect-

ing rods 173 upwardly to cause the arms 164 to pivot about the pins 165 and to withdraw the ironing shoe 101 from the surface of the roll 15.

The roll drive interrupting means

With the mechanism as thus far described, the arrangement is such that when the operator actuates the knee control 121, the roll 15 and shoe 101 will operate simultaneously so that the roll 15 will begin to rotate as the ironing shoe 101 moves into pressing engagement with it and the shoe 101 will be caused to move away from the roll 15 whenever the rotary movement of the roll ceases. Under ordinary circumstances this type of operation is preferable since there is no danger that the ironing shoe 101 will bear against the given portion of the fabric surface of the roll 15 for a sufficient length of time to cause scorching, but in the prior art this mode of operation has at times been objectionable in that it did not readily permit the operator to interrupt the rotation of the roll and yet hold the roll and shoe in engagement.

It will be appreciated that at certain times it becomes quite important that means be provided to stop the roll while maintaining the roll and shoe in engagement in order to accomplish spot ironing, wherein a small area of the work may be subjected to continuous ironing in order to properly meet certain conditions that arise in practice. Such conditions may arise in a number of situations, as, for example, in the event that the operator encounters an unduly damped portion of the work and wishes to facilitate drying by means of continuous contact between the work and the heated ironing shoe. It has, therefore, been found desirable to provide means for interrupting the normal operation of the machine in order that the roll 15 may be momentarily stopped while it is engaged by the heated ironing shoe 101.

In the preferred embodiment of the invention illustrated, the operator may accomplish this result by depressing the treadle 181, which extends between the two vertical leg members 11 of the machine cabinet 10. The treadle 181 is secured to a pivoted shaft 182 extending between the legs 11, and one end of this shaft 182 is secured to a crank 183 connected by means of a pull rod 184 to one arm of a bell crank 185 pivoted on a pin 186 within the leg 11. The other arm of the bell crank 185 is connected by means of a pull rod 187 to a crank 188 secured to a rock shaft 189 journaled in a bearing 191 formed integral with the gear case 17. The crank 188 is preferably secured to the rock shaft 189 by means of a set screw 192, and if desired, a stop lug 193 may be positioned between two bifurcated end portions 194 of the crank 188 in order to limit the rocking movement of the rock shaft 189.

Within the gear case 17, a shifting yoke 195 is secured to the rock shaft 189 in any suitable manner, as by the set screw 196 and is so arranged as to have its bifurcated operating portions 197 extend upwardly to engage a collar 198 affixed to the slide shaft 144, which, as hereinbefore described, serves to control the operation of the clutch 59.

When the operator desires to interrupt the rotary movement of the roll 15 without disturbing the pressure relationship between the roll and shoe, she depresses the treadle 181 with her foot. The movement of the treadle 181 will be transmitted through the several cranks and links to the slide shaft 144 and will be effective

to disengage the clutch 59 through which the roll 15 is driven and allow the roll 15 to remain stationary until the treadle 181 is released. When the treadle 181 is released, the clutch 59 will re-engage to again impart rotary movement to the roll 15, and the treadle 181 and associated linkages will be returned to their original positions by the spring 148 carried on the slide shaft 144.

10 *The burnishing means*

The machine structure as thus far disclosed will be seen to permit continuous ironing of the fabrics passing between the ironing roll and shoe as these fabrics pass along the path of feeding movement and will also permit this feed movement to be interrupted momentarily to accomplish stationary pressing of portions of the fabric. It is desirable, however, that the ironing shoe 101 be maintained in constant surface movement with respect to the fabric being ironed in order to exert a burnishing action on the fabric and thus accomplish a substantial improvement in the appearance of the work delivered from the machine. It is well known that the surface of fabrics being ironed will present a better finish and appearance if the ironing shoe is in constant motion with respect to the fabric during the ironing operation and it is for this reason that the present machine is provided with burnishing mechanism whereby the ironing roll and shoe may be kept in constant relative movement even during the periods in which the feeding movement of the roll is interrupted.

15 35 The burnishing mechanism is driven by means of a bevel gear 201 keyed to the sleeve 25 on the shaft 28 at a point between the worm gear 27 and the pinion gear 34 heretofore described. This bevel gear 201 meshes with and drives a bevel gear 202 keyed to a driving clutch sleeve 203 journaled for rotation in a bearing 199 formed in an inwardly extending flange 200 integral with the gear case 17. The clutch sleeve 203 is provided with an enlarged head portion 204 including a plurality of clutch teeth 205 adapted to be engaged by corresponding clutch teeth 206 of a driven clutch element 207. The clutch element 207 is slidably splined to a crank shaft 208 journaled at its outer end in a bearing 209 formed in the wall of the gear case 17 and provided with a reduced end portion 211 rotatably mounted in the clutch sleeve 203. This crank shaft 208 is mechanically connected to the ironing shoe 101 in order to drive the shoe in a longitudinally reciprocating path of motion, and to this end a crank 213 is provided at the outer end of the shaft 208, and a connecting rod 214 is mounted thereon by means of the crank stud 215. The connecting rod 214 transmits reciprocating movement from the crank 213 to the lower ends of each of the arm mounting levers 216, which are connected at their lower extremities by the link 218 extending between the studs 219 (see Fig. 5).

20 40 45 50 55 60 65 70 75 Each of the levers 216 is pivotally mounted on a stud 221 threaded into each of the pair of ironing shoe supports 163 heretofore described. It will also be seen that the pins 165 on which the ironing shoe support arms 164 are pivoted are mounted in the upper extremities of each of the levers 216 in such a manner that the reciprocating movement imparted to the levers by the crank 213 will cause the pair of ironing shoe supporting arms 164 to swing back and forth to

impart a limited longitudinal movement to the shoe 101.

To facilitate this action and prevent any possibility of binding between the pivotal connection 223 by which the ironing shoe 101 is supported, each of the supporting brackets 224 is pivotally mounted on the shoe 101 by means of a stud 225 extending through the orifice 226 in the base 227 of the supporting bracket 228. This construction provides a universal type joint between the arms 164 and the shoe 101 and permits the arms 164 and levers 216 to swing back and forth in a parallel-link motion to provide the desired degree of longitudinal motion for the ironing shoe.

This burnishing mechanism makes it possible to maintain surface movement at all times during the operation of the machine, since the shoe 101 may be caused to reciprocate constantly with respect to the roll 15. However, when the roll 15 is rotating in such a manner as to advance the work under the shoe, the motion of the roll provides sufficient surface movement and it is then unnecessary, and in some instances undesirable, to reciprocate the shoe. For this reason control mechanisms are provided responsive to the operation of the roll drive interrupting mechanisms heretofore described, in such a manner that when the operator depresses the foot pedal 181, the roll 15 will cease to advance and the shoe 101 will begin its reciprocating movement. Similarly, when the foot pedal 181 is released the shoe 101 will cease its reciprocating movement and the roll 15 will again advance in a rotary movement in the direction of the path of feed. It will be understood, of course, that this cycle of operations may take place while the roll and shoe remain in constant pressure engagement and operate entirely independently of the knee control 121 which is common to the mechanism driving the roll 15 and the pressure mechanism serving to engage or disengage the roll and shoe.

In order that the reciprocating drive control be responsive to the operation of the roll drive interrupting means, a clutch disengaging arm 231 is secured to the rock shaft 189 heretofore described. This clutch disengaging arm 231 is mounted at the extreme end of the rock shaft 189 adjacent the bearing 232 in which the shaft 189 is journaled and in a position adjacent the driven clutch element 207, which is provided with a pair of diametrically opposed control pins 233 which may be engaged or disengaged by the arm 231 in such a manner as to move the driven clutch element longitudinally along the splined shaft 208 in order to engage or disengage the teeth 205 and 206.

During the normal operation of the machine, the arm 231 maintains the position illustrated in Figs. 7, 10 and 11, and holds the clutch element 207 in disengaged position. However, when the foot pedal 181 is depressed to interrupt the rotary movement of the roll 15, the rock shaft 189 moves in a counterclockwise direction, as viewed in Fig. 11, and swings the arm 231 from the solid line position shown in the drawings to the dotted line position. This motion, of course, releases the control pin 233 and allows a coiled compression spring 234 to snap the clutch element 207 into interlocking engagement with the driving clutch element 204. The driving clutch element 204 is directly geared to the shaft of the motor 18 by reduction gear train heretofore described and is therefor constantly rotating at all times when the motor 18 is energized. It follows that when-

ever the foot pedal 181 is depressed to operate the rock shaft 189 and slide the shaft 144 longitudinally to disengage the clutch mechanism 59 and interrupt the rotary feeding movement of the roll 15, the clutch 204—207 will simultaneously engage to rotate the crank member 213 and impart longitudinal reciprocating movement to the ironing shoe 101. When the foot pedal 181 is released, the coiled compression spring 148 on the longitudinally sliding shaft 144 will return the rock shaft 189 to its original position and move the clutch disengaging arm 231 back into the path of rotary movement of the control pins 233, and as either of these control pins 233 engage the inclined cam surface 235 of the disengaging arm 231, the continued movement of the clutch element 207 will force the element 207 longitudinally of the splined shaft 208 and disengage the clutch. The several parts may then remain in disengaged position until such time as the foot pedal 181 is again operated.

In certain instances it may be desirable to provide a burnishing mechanism which may operate independently of the operation of the other parts of the mechanism rather than by means of the automatic control just described, and to this end a clutch disengaging arm 241 is mounted on a rock shaft 242 journaled in suitable bearings 243 within the gear case 11, and is provided with a crank arm 244 and connecting link 245 pivoted at 246 in such a manner that the movement of the clutch disengaging arm 241 may be manually controlled by the hand control lever 247. The lever 247 is mounted on a stub shaft 248 journaled in a bearing 249 in the roll support bracket 16 and is provided at its inner end with a crank 251 pivotally connected to the upper end of the connecting link 245 by crank pin 252 (see Figs. 6, 7 and 8).

Whenever the operator desires that the burnishing mechanism be rendered inoperative, the manual control lever 247 may be moved approximately one-fourth turn in a counterclockwise direction, and this motion will be effective to operate through the connecting link 245 to rock the rock shaft 242 and move the clutch disengaging lever 241 into the path of movement of the control pins 233 carried on the clutch element 207. The operation of the clutch disengaging arm 241 is identical with the operation of the similar arm 231 hereinbefore described.

The arms 231 and 241 are so positioned with respect to the clutch member that the operation of either of these arms will be effective to stop the clutch control pins 233 at one of two diametrically opposed positions. By this construction it is possible to fix the relative angular position between the crank member 213 and the clutch control pins 233 so that whenever the clutch 204—207 is disengaged, the crank stud 215 will come to rest in a position either directly above the center line of the splined shaft 208 or directly below the center, in order that the ironing shoe 101 will come to rest in a central position at the mid-point of its path of longitudinal burnishing movement and in a predetermined centralized relationship with respect to the position of the roll 15.

The operation

While it is believed that the operation of the machine should be apparent from the foregoing description, it will nevertheless be briefly reviewed.

The operator will first start the motor 18 by

closing the electrical switch 300, which remains closed during the entire period of operation. Material to be ironed may now be placed on the roll 15 adjacent the ironing shoe 101 and the knee control 121 actuated. The movement of the knee control lever 121 will be transmitted through the link 123 to the crank 125 and thence from the crank 121 to the stop lever 116 in order that the dog 115 of the rocker arm 112 will be momentarily disengaged by the stop arm 116. When this disengagement takes place, the tension spring 133 will pivot the rocker arm 112 about the hub 110 and cause the slide plate 105 to engage the tooth 109 in the toothed disk 102, which is being driven by the motor 18 operating through the worm and gear 26 and 27. When the tooth 109 engages the disk 102, the entire casting 104 will move through one half revolution of movement at which time the dog 114 will engage the stop arm 116 causing the tooth 109 to bring the casting 104 and its associated mechanisms to a standstill. However, the rotary movement of the casting 104 will have caused the cam surface 141 to disengage the cam extension 143 of the shifting yoke 142 and will thus engage the clutch mechanism 59 and complete the driving connection between the motor 18 and the roll 15. This will cause the roll 15 to begin its movement and at the same time the ironing shoe 101 will be moved into resilient engagement with the roll by means of the eccentric 151 operating through the eccentric strap 152 and pressure spring 156, in order to exert a rocking movement on the shaft 161, which will be transmitted through the cranks 171 and links 173 to the ironing shoe arms 164 in such a manner as to draw the shoe 101 downwardly into engagement with the surface of the ironing roll 15. This relationship of these parts will continue until the knee control lever 121 is again actuated to disengage the shoe 101 and stop the movement of the roll 15 or until the foot pedal 181 is actuated.

When the foot pedal 181 is operated, motion is transmitted through the cranks 183, 185 and 188 to the rock shaft 189 and the shifting yoke 195, which will move the slide shaft 144 longitudinally in such a manner as to cause the shifting yoke 143 to disengage the clutch 59 and thus interrupt the rotary feeding movement of the roll 15 while it is still being engaged by the heated ironing shoe 101. The actuation of the foot pedal 181 and rocking movement of the rock shaft 189, will simultaneously cause the clutch 204-207 to engage and impart rotary movement to the crank 113 in such a manner as to move the shoe 101 in a successively repeated path of movement longitudinal of the axis of the roll 15 and normal to the direction of feed of the work passing between the roll and shoe. The arrangement is such that the roll and shoe are in substantially constant relative surface movement at all times, both when the roll is rotating to advance the fabrics being ironed under the shoe and when the movement of the roll has been interrupted to provide spot ironing on certain portions of the work.

When the operator removes her foot from the pedal 181, the clutch 59 will be re-engaged by means of the spring 148, the clutch disengaging the arm 231 will again move into the path of movement of the clutch control pins 231, and the continued movement of the clutch element 207 will disengage the clutch 204-207 and bring the crank 231 to a stop in a predetermined position, 75

such that the shoe 101 will come to rest in proper longitudinal relationship with the roll 15.

While the preferred form of this invention has been shown and described in compliance with the patent statutes, it is nevertheless subject to numerous alterations and modifications without departing from the spirit of the invention and should not, therefore, be limited except as by the scope of the appended claims.

I claim:

1. In a clothes ironing machine including a rotatably mounted feeding and pressing roll, a cooperating ironing shoe including a portion adapted to engage the surface of the feeding and pressing roll and to engage the surface of fabrics being passed between said roll and shoe to iron the fabrics, supports for said feeding and pressure roll and for said ironing shoe, a motor, power transmission means comprising a reduction gear train to rotate said roll, pressure means for said shoe; the combination of control means for simultaneously operating said power transmission means and said pressure means, additional feed-interrupting control means comprising a clutch adapted to be operated by a foot pedal to provide spot ironing, additional burnishing means comprising the said shoe and clutch and an eccentric adapted to impart reciprocatory movement to said shoe, and means for simultaneously operating said feed-interrupting control and said burnishing means.
2. In an ironing machine including a rotatable feeding and pressing roll, a cooperating ironer shoe adapted to be moved into pressing engagement with said roll, power operated means to rotate said feeding and pressing roll to advance the fabrics being ironed in a predetermined direction of feed between said roll and said ironing shoe, power operated means to move said roll and shoe into cooperating pressing engagement, and common control mechanisms whereby the said roll and shoe may be caused to engage in synchronous-timed relationship with the commencement of feeding movement of said feed roll and be caused to disengage in synchronous-timed relationship with the cessation of said feeding movement of said roll, the combination of means for supporting said feed roll and ironer shoe to permit limited reciprocating movement of said shoe in a direction longitudinal of the axis of said pressing roll, driving means including a power source, a clutch, and an eccentric to cause said movement between said shoe and roll, means including a foot-operated control element to momentarily interrupt the feeding movement of said roll while said roll and shoe remain in engaged pressing relationship, means responsive to the operation of said feed interrupting means to operate the aforesaid clutch.
3. In an ironing machine including a rotatable feeding and pressing roll, a cooperating ironer shoe adapted to be moved into pressing engagement with said roll, power operated means to rotate said feeding and pressing roll to advance the fabrics being ironed in a predetermined direction of feed between said roll and said ironing shoe, power operated means to move said roll and shoe into cooperating pressing engagement, and common control mechanisms whereby the said roll and shoe may be caused to engage in synchronous-timed relationship with the commencement of feeding movement of said feed roll and be caused to disengage in synchronous-timed relationship with the cessation of said feeding movement of said roll, the combination of means for

supporting said feed roll and ironer shoe to permit limited movement of said shoe in a direction other than the direction of feed of the fabrics being ironed, driving means including a power source, a clutch, and an eccentric to cause said movement between said shoe and roll, means including a foot-operated control element to momentarily interrupt the feeding movement of said roll while said roll and shoe remain in engaged pressing relationship, means responsive to the operation of said feed interrupting means to operate the aforesaid clutch.

4. An ironing machine including an ironing roll, a heated ironing shoe, power operated engaging means adapted to move said ironing roll and heated ironing shoe into cooperating pressing engagement with each other, power-operated roll-driving means for imparting rotary movement to said ironing roll, automatic control mechanisms including a clutch responsive to knee-control actuation by the operator adapted to simultaneously operate said engaging means and said roll driving means, power-operated shoe reciprocating means including a motor, a reduction gear train, and a clutch and an eccentric for imparting relative reciprocating movement in a direction longitudinal of the axis of said roll be-

tween said ironing roll and shoe, roll drive interrupting means including a foot pedal operable independently of aforesaid automatic control mechanisms, and means responsive to the operation of said roll drive interrupting means for causing said shoe-reciprocating means to operate.

5. An ironing machine including an ironing roll, a heated ironing shoe, power operated engaging means adapted to move said ironing roll and heated ironing shoe into cooperating pressing engagement with each other, power operated roll-driving means for imparting rotary movement to said ironing roll, automatic control mechanisms including a clutch adapted to simultaneously operate said engaging means and said roll driving means, power-operated shoe reciprocating means including a clutch for imparting relative reciprocating movement in a direction longitudinal of the axis of said roll between said ironing roll and shoe, roll drive interrupting means operable independently of aforesaid automatic control mechanisms, and means responsive to the operation of said roll drive interrupting means for causing said shoe-reciprocating means to operate.

JOHN A. CASTRICONE.
